UNITED STATES PATENT OFFICE

FRANK KESSLER AND ALBERT GEORGE FORSTER, OF LIVERPOOL, ENGLAND, ASSIGNEES
TO ASSOCIATED TELEPHONE AND TELEGRAPH COMPANY, OF CHICAGO, ILLINOIS, A
CORPORATION OF DELAWARE

TELEPHONE SYSTEM

Application filed May 11, 1929, Serial No. 362,194, and in Great Britain July 2, 1928.

The present invention relates to interconnecting arrangements for use in telephone systems and is more particularly concerned with the mounting of the terminal strips or the like upon which the connections from the banks of automatic switches are terminated. It is of course well known that the grouping of the switches will generally require to be changed from time to time and for this reason if for no other it is undesirable that the connections should be permanent, but rather should be so arranged that subsequent alterations can be made with the minimum of trouble and dislocation. It is usual to mount automatic switches on racks in horizontal rows which are known as shelves and generally comprise either 10 or 20 switches and the connections from the bank contacts are then taken to terminal strips at one end of the rack, the terminals associated with the various levels being arranged horizontally, preferably at substantially the same height as the shelf to which they belong.

This arrangement has the disadvantage that since the number of contacts in a level is usually 10 and moreover since the different contacts engaged by the various wipers of a set are usually staggered on the terminal block to permit bare wire multiplying to take place, the overall width of the terminal block becomes excessive and moreover the length of the wires employed for the bare wire multiplying between the various switches is also large so that they are difficult to manipulate both when they are originally put in place and when they have to be removed subsequently if alterations become desirable. On the other hand for convenience of maintenance it is not usual to mount more than five or at the most six shelves of switches one above another owing to limitations of height and accordingly since all the switches of a shelf will usually be multiplied together, if the terminal blocks are arranged so that the contacts corresponding to the various shelves are arranged horizontally rather than vertically as was previous practice a considerable saving in the horizontal dimension of the ter-

minal strips can be effected and a generally more compact mounting secured.

According to the invention, therefore, a mounting arrangement is provided for terminal blocks of automatic switches in which the terminals to which the contacts of the various shelves of switches are connected are mounted adjacent to one another in a horizontal row so as to reduce the horizontal dimension of the terminal frame.

According to another feature of the invention the connections from the banks of the switches are terminated on standard tag blocks arranged one above the other with their longer dimension vertical.

The invention will be better understood from the following description of one method of carrying it into effect which should be taken in conjunction with the accompanying drawings. These drawings show a preferred embodiment but it will be understood that various modifications could be made in the constructional details without exceeding the scope of the invention.

Referring now to the drawings, Fig. 1 is a front elevation of a part of a rack with its corresponding terminal assembly mounted at the right hand end and shows also the terminal assembly of a similar rack which is not shown but would be located on the right of the figure. Fig. 2 shows on a somewhat larger scale a back view of the rack and terminal assembly shown in Fig. 1. Fig. 3 is an enlarged view corresponding to Fig. 1 and permits a better grasp of the smaller details. Fig. 4 shows diagrammatically a portion of the two adjacent terminal blocks and illustrates the arrangement for bare wire multiplying between the terminal blocks of adjacent racks. Fig. 5 is a diagrammatic plan view of the two racks under consideration, while Fig. 6 represents an alternative arrangement in which the racks are butted together at the ends remote from their terminal blocks so that these latter come on the outside.

Referring now to Figs. 1, 2 and 3 the rack comprises the usual main uprights 1 connected by the cross members 2 corresponding to the individual shelves. These cross mem-

bers are connected by the vertical members 3 which are provided with the usual bayonet pins permitting the switches to be detachably mounted thereon in well-known manner. 5 The uprights 1 terminate in the feet 4 which are of suitable shape and sufficient size to distribute the weight of the rack over an appropriate portion of the floor area. The switches 5 of one shelf and their associated 10 banks 6 are shown in position and it will be understood that the switches of other shelves will be accommodated in corresponding positions, these switches being omitted however in order not to complicate the drawing un- 15 necessarily. The terminal blocks to which the various connections extend are shown at 7, these comprising standard tag blocks mounted one above the other with their longer dimension vertical and used in conjunction 20 with wooden fanning strips 8 of known type. The bank cabling, which terminates at the back of the blocks and is therefore more clearly seen in Fig. 2 is indicated at 9. The switches shown are presumed to be provided 25 with 400-point banks so that if each tag block is provided with 25 rows of contacts as is convenient, 16 tag blocks in all will be necessary for terminating the various connections of a rack of switches. 30 As is well appreciated by those skilled in the art there are three sets of connections which require to be made to the terminal blocks, firstly the bank cabling which is of a permanent nature and is preferably termin- 35 ated at the rear, secondly the so-called jumping which comprises the connections from the terminal block to the outgoing trunk lines and thirdly the commoning necessary in a large system between the various shelves of 40 switches which is preferably effected by bare wires though insulated wires may also be used. With the arrangement shown, the commoning wires can be very short and this in addition to facilitating manipulation of these 45 wires, considerably reduces any danger of inductive disturbance arising between the various circuits. It is generally considered desirable that the commoning and jumping should both be done on the front of the terminal blocks so that any alterations which may 50 need to be made subsequently in these connections will not disturb the permanent bank cabling. In this case the tags are provided with a single notch at the back and a double 55 notch at the front so that the necessary soldered connections may readily be made. In some cases, however, it may be considered desirable to have the jumping and commoning on opposite sides of the block as then 60 alterations to one can be made without disturbing the other, and in this case the portion of the tag with the double notch will require to be at the rear. This however is easily taken care of by merely reversing the block. 65 It will be appreciated that with the ar-

rangements shown in Figs. 1, 2 and 3 and diagrammatically in Figs. 4 and 5, commoning between adjacent racks can be readily effected by merely extending the bare wire or alternatively covered wire connections 16 70 across from one terminal block to the other. In case however this is not possible for instance with the arrangement of Fig. 6 or where the commoning has to be extended to other racks, it may readily be done by the 75 use of jumper wires or tie cables, conveniently connected between vertical rows of terminals which are preferably specially provided for this purpose at either end of the switch terminals as shown clearly in Fig. 4. As may be 80 seen from Fig. 1 the rack is assumed to comprise only 5 shelves and of the 7 vertical rows of terminals shown in Fig. 4 the first and last are set aside for making connections if necessary to the preceding and subsequent ranks 85 of switches respectively. The separate terminal blocks which are required for the outgoing trunks are in this case preferably mounted separately on the front of the frame at substantially the height 90 corresponding to the tag block terminals of the level in question as shown at 10. By this means the length of the jumper wires required is reduced to a minimum and this arrangement therefore has advantages over the 95 arrangement hitherto employed in which all the terminal blocks are located at the top of the frame. It may be convenient also to mount on the front of the terminal frame analysis 100 metering or similar equipment and this is indicated at 11, it being understood that the panel shown is mounted at right angles to the plane of the rack. This however is by no means essential and the panel can be mounted at the most convenient angle and at any suitable height. It is generally considered desirable nowadays also to provide that switches are routine tested at regular intervals and for this purpose special access switches are necessary for connecting the switches under consideration with the routine equipment. It will probably therefore be economical to mount these routine testing switches also on the terminal frame and a pair of such switches 110 are shown at 12, a tag block associated with them being also mounted on the front at 13. The arrangement preferably includes also metal covers 14 which are mounted at the back of the terminal blocks and serve to protect the terminals and bank cabling from injury. Miscellaneous relay groups may conveniently be mounted on the plates 15 suitably located between the switches and the terminal blocks or on the terminal frame occupying the same mounting space as the outgoing terminal blocks 10. 115 120 125

According to the invention, therefore, an interconnecting arrangement has been devised which economizes space and gives more 130

satisfactory results than arrangements hitherto employed, while at the same time since the rack and its terminal assembly form a self-contained unit it is possible to effect the majority of the cabling, jumpering and commoning before the unit leaves the factory so that the work necessary on the site where conditions may be less advantageous is reduced.

What we claim as new and desire to secure by Letters Patent is:—

1. The combination with a switch supporting rack, of a plurality of shelves of automatic switches mounted thereon, a distributing frame comprising a plurality of parallel vertical rows of terminal pins, each of said rows corresponding to one of said shelves, and multiple connections between the bank contacts of the respective shelves and the corresponding row of terminal pins.
2. The combination with a group of automatic switches, of a contact bank for each switch, multiple connections between corresponding contacts of each bank, a connecting rack comprising a single vertical row of terminal pins, and multiple connections from the contacts of the last bank of the group to successive ones of said terminal pins.
3. The combination with groups of multi-contact banks, of multiple connections between corresponding contacts of the banks comprising each group, a connecting rack comprising a plurality of vertical rows of terminal pins, each row corresponding to one of said bank groups, and multiple connections from the contacts of one bank of each group to the terminal pins of the corresponding row.
4. The combination with a rack supporting a plurality of shelves of automatic switches, of a bank multiple for each shelf of switches, a connecting cable from each bank multiple, and a plurality of parallel vertical rows of terminal pins, each of said rows terminating one of said cables.
5. The combination with a rack supporting a plurality of shelves of automatic switches, of a bank multiple for each shelf of switches, a connecting cable from each bank multiple, a plurality of parallel vertical rows of terminal pins, each row terminating one of said cables, and an inter-shelf multiple comprising connections between corresponding pins of each vertical row.
6. The combination with a plurality of racks each supporting a plurality of shelves of automatic switches, of a bank multiple for each shelf of switches, a connecting cable from each bank multiple, a cross-connecting terminal for each rack comprising a plurality of parallel vertical rows of terminal pins, each row terminating one of said cables, an inter-shelf multiple comprising connections between corresponding pins of each row, and an inter-rack multiple comprising jumper

connections between corresponding pins of a row on each rack.

7. An inter-connecting arrangement for automatic switchboards in which automatic switches are mounted on shelves on a supporting rack and in which the complete bank multiple of each shelf of switches is connected to a group of terminal pins arranged in a single vertical row, terminal blocks supporting said rows of pins in parallel position with corresponding pins of each row aligned in the same horizontal plane, and means for mounting said terminal blocks on the supporting rack.

8. An inter-connecting arrangement for automatic switchboards in which automatic switches are mounted on shelves on a supporting rack and in which the complete bank multiple of each shelf of switches is connected to a group of terminal pins arranged in a single vertical row, terminal blocks supporting said rows of pins in parallel positions with corresponding pins of each row aligned in the same horizontal plane, and multiple connections between said horizontally aligned pins.

9. An inter-connecting arrangement for automatic switchboards in which automatic switches are mounted on shelves on a supporting rack and in which the complete bank multiple of each shelf is connected to a group of terminal pins disposed in a single vertical row, an additional vertical row of terminal pins for terminating jumper cables extending to adjacent racks, and terminal blocks supporting said rows of pins in parallel positions with corresponding pins of each row aligned in the same horizontal plane.

10. An inter-connecting arrangement for automatic switchboards in which automatic switches are mounted on shelves in a supporting rack and in which the complete bank multiple of each shelf is connected to a group of terminal pins disposed in a single vertical row, an additional vertical row of terminal pins for terminating jumper cables extending to adjacent racks, terminal blocks supporting said rows of pins in parallel positions with corresponding pins of each row aligned in the same horizontal plane, and multiple connections between said horizontally aligned pins.

11. In a telephone system, an automatic switch supporting rack, an interconnecting rack assembled integrally with said supporting rack, and a single vertical row of terminal pins on said interconnecting rack for each shelf position on the supporting rack.

12. In a telephone system, an automatic switch supporting rack, an interconnecting rack assembled integrally with said first rack, a single vertical row of terminal pins on said second rack for each shelf position on said first rack, and an additional row of vertically disposed terminal pins for multiplying with

the interconnecting racks of adjacent supporting racks.

13. In a telephone system, an automatic switch supporting rack, an interconnecting rack assembled integrally with said first rack, a single vertical row of terminal pins on said interconnecting rack for each shelf position on the supporting rack, and a removable metal cover on said interconnecting rack for protecting said terminal pins from injury.
14. In a telephone system, an automatic switch supporting rack, an interconnecting rack assembled integrally with said first rack, a single vertical row of terminal pins on the second rack for each shelf position on said first rack, terminal blocks mounted on said first rack adjacent to said second rack, and terminal pins in said blocks for terminating the conductors of outgoing trunk cables.
15. In a telephone system, an automatic switch supporting rack, an interconnecting rack assembled integrally with said first rack, a single vertical row of terminal pins on the second rack for each shelf position on the first rack, outgoing trunk and multiple cable terminating pin blocks mounted on the first rack adjacent to the second rack, and jumper cables for connecting the terminal pins of the rack with the pins of the blocks.
16. In a telephone system, two adjacently mounted switch-supporting racks each equipped with an integrally-assembled interconnecting rack located respectively at the adjacent ends of the supporting racks, a vertical row of terminal pins on each interconnecting rack for each shelf position of the associated supporting rack, and a vertical row of terminal pins on each interconnecting rack for connecting the two racks.
17. In a telephone system, two adjacently mounted switch-supporting racks each equipped with an integrally-assembled interconnecting rack located respectively at the adjacent ends of the supporting racks, a plurality of parallel vertical rows of terminal pins on each interconnecting rack, each of said rows terminating a bank cable from one of the shelf positions of the associated supporting rack, and an additional vertical row of terminal pins parallel with said other rows on each of said interconnecting racks, said additional rows of terminal pins terminating a multiple cable connecting the two racks.

In testimony whereof we have signed our names at Liverpool, England, this 18th day of April, 1929.

FRANK KESSLER.
ALBERT GEORGE FORSTER.
